FEELER-MOTION FOR LOOMS.

1,282,974.

Specification of Letters Patent. Patented Oct. 29, 1918.

Application filed October 11, 1916. Serial No. 125,092.

To all whom it may concern:

Be it known that I, EDWARD S. STIMPSON, a citizen of the United States, residing at Hopedale, in the county of Worcester and State of Massachusetts, have invented an Improvement in Feeler-Motions for Looms, of which the following description, in connection with the accompanying drawings, is a specification, like characters on the drawings representing like parts.

The invention to be hereinafter described relates to feeler motions for looms, whereby, when the filling in the shuttle becomes substantially exhausted, a train of mechanism is caused to be actuated to effect a change in the condition of the loom.

The change in the condition or operation of the loom may be the stoppage thereof, or, as is more frequently the case, a fresh supply of filling may be automatically furnished. Looms containing feeler motions to effect the desired results are commonly known as "feeler looms", and where replenishment of filling is effected, it may be done either by changing the nearly exhausted filling carrier or bobbin in the shuttle for another having a working supply of filling wound thereon, or by changing the shuttle for another containing a working supply of filling.

Ordinarily, the feeler is arranged to enter the shuttle and engage the filling, and to be moved frontward from its full rearward feeling position on each detecting beat, but this recurring action is injurious to the filling. This is particularly so in that type of feeler motion known as the "side-swipe" feeler, and is due to the fact that the feeler member is so arranged that on each detecting beat it has a tendency to move longitudinally of the shuttle and is held from such movement by engagement with the filling until substantial exhaustion is reached, whereupon, the filling is no longer able to hold the feeler member and it moves longitudinally of the shuttle to initiate filling replenishment.

An important feature of the present invention, therefore, consists of means for holding the feeler member frontward of its rear feeling position so that it may engage the filling during only a small part of the normal feeling action on a detecting beat,

and continue to be so held until the feeler member detects approaching exhaustion, whereupon it is permitted to move rearwardly into full feeling position and perform its side swipe feeling operations. In this aspect of the invention, the feeler member has a dual function,—a measuring function to measure the diameter or amount of the filling in the shuttle, and upon the detection of a predetermined diameter of filling, to move into position to perform its side-swipe feeling function and control of the replenishing operation.

While performing its measuring function, it is important that the feeler member shall not move or tend to move longitudinally of the shuttle, because this would injuriously affect the filling at a time when any such movement or tendency to such movement is functionally useless. Another important feature of the invention, therefore, consists of means for locking the feeler member from movement longitudinally of the shuttle while it is performing its measuring function.

In that form of side-swipe feeler where means are employed for moving the feeler longitudinally of the shuttle upon substantial exhaustion of filling, some stress is liable to be imparted to the feeler in a direction longitudinally of the shuttle due to the action of said means when the feeler itself is held from such movement. A further important feature of the invention, therefore, consists in means which permits the front or forward portion of the feeler to move laterally under such conditions.

In addition to the above, other important features of the invention will be hereinafter described in connection with the accompanying drawings which show one good practical form thereof, and then the various features of the invention will be definitely set forth by the claims.

The term "substantial exhaustion" is herein used in its commonly-accepted sense, meaning thereby, that when the ultimate function of the exhaustion-indicating mechanism is performed, there will still remain a small portion of filling in the filling carrier or bobbin in the shuttle.

In the drawings:—
Figure 1 is a perspective view showing a

portion of the loom frame and the feeler motion connected therewith, and a fragmentary portion of the shuttle-box and shuttle;

5 Fig. 2 is a plan view of the feeler motion detached and having the cover plate removed;

10 Fig. 3 is a perspective view showing the feeler motion when it ascertains by measuring the diameter of the filling in the shuttle that the filling is approaching substantial exhaustion, the cover or cap plate being lifted and shown in part to illustrate the stop to be described; and

15 Fig. 4 is a perspective view showing the action of the side-swipe feeler when the filling has become substantially exhausted.

20 The loom frame 1, only part of which is shown in the drawings, may be of any usual character, and is illustrated as being provided with the usual shipper stand 2 in the slot 3 of which the shipper 4 is movable.

25 The shuttle-box 5 carried by the usual lay and the shuttle 6 which is adapted to hold the filling carrier 7 and its load of filling 8 are each provided with the usual slot in the side walls thereof, through which the feeler member may pass on a detecting beat to perform its detecting function. The feeler member is of that type usually known in the art as the "side-swipe" feeler, that is, the feeler moves in a direction longitudinally of the shuttle when substantial exhaustion of filling is reached in order to initiate the operation of a train of mechanism for effecting a change in the loom condition, as for instance, to initiate filling replenishment. The feeler member is supported as usual in front of the lay and extends rearwardly.

30 40 It is normally under the influence of a light spring which tends to push it rearwardly. It is usual in the side-swipe type of feeler to exert upon the feeler member on each detecting beat, a tendency to move in a direction longitudinally of the shuttle when the engaging end of the feeler is in contact either with the filling or the filling carrier in the shuttle; and if the feeler member be in its full rearward position on a detecting beat

45 50 when a working supply of filling is present in the shuttle, the wound mass of filling is called upon to resist the tendency to side movement of the feeler member, thereby causing injury to the filling in the shuttle.

55 60 65 As a matter of fact, it is not necessary for the feeler member to perform its side-swipe feeling function with the consequent injurious effect upon the yarn so long as a full working supply of filling is present; but this function may well be suspended during the greater part of the weaving operation, or until the filling in the shuttle approaches a condition of substantial exhaustion. Therefore, one of the purposes of the present invention is to provide means whereby the

feeler member may have its side-swipe feeler function suspended until by its detecting action, it ascertains or detects that the filling in the shuttle is approaching the critical stage when filling replenishment is desired, and thereupon have its side-swipe detecting function restored.

70 Extending from the loom frame and preferably at the side of the shipper stand 2, is a bracket 9 adapted to sustain the feeler member and its associated parts in such position that the feeler member may enter the shuttle on each detecting beat and perform its detecting function. The feeler stand for supporting the feeler member, may be of any desired or convenient construction, and in the present instance of the invention it comprises a base piece or support 10 between which and a cap or cover piece 11, the feeler member is mounted for movement toward and from the front of the loom and longitudinally of the shuttle. The support 10 and cover 11 are each provided with a slotted flange 12 held together by a suitable means such as the screw 13 and adjustably secured by a bolt 14 to the bracket 9 or other convenient sustaining means.

75 It is desirable in the feeler type of looms, that the feeler member shall have yielding movement toward the front of the loom when it is engaged by the filling or carrier in the shuttle on a detecting beat; and to this end, various forms of mechanism will suggest themselves to those skilled in the art. In the present instance of the invention, however, the feeler member 15 is mounted upon a carrier 16 with respect to which it is movable longitudinally, that is, toward and from the front of the loom. To this end, the carrier 16 has the guiding lugs 17 and 18 which form suitable guideways for guiding the feeler member 15. Rising from the cover plate 11 is the arm 19 carrying a spring 20, the downwardly-extending end 21 of which is adapted to engage the feeler member 15 and normally tends to move it in a direction toward the rear of the loom. In the present instance of the invention, the downwardly-extending end 21 of the spring engages an opening 22 and normally acts to move the feeler member rearwardly, the construction being such that on each detecting beat the feeler member 15 may be moved forwardly.

80 100 105 110 115 120 125 130 The feeler member 15 is provided with a roughened, toothed, or serrated feeling end 23 which is adapted to engage the filling or the filling carrier in the shuttle, the construction being such that should the feeler member 15 be in feeling position, and free to move longitudinally of the shuttle, it will, on a detecting beat when a working supply of filling is present, be held from such longitudinal movement; but should the filling be substantially exhausted and not able to

prevent movement of the feeler longitudinally of the shuttle under the impulse of its actuating means, the feeler member will move, and by such movement initiate filling replenishment, as will presently appear.

To prevent injurious effect upon the filling that is liable to occur upon the intermittent engagement of the feeler member therewith, while a working supply is present, and said 5 feeler member is free to move longitudinally of the shuttle under its actuating means, the present invention contemplates means for holding the feeler member forward of its rear or feeling position so long as a working 10 supply of filling is present and confine the feeler member to a measuring function, such that when the feeler member indicates that a predetermined diameter of filling has been 15 reached, the said means will free the feeler member to move into its full rearward feeling position and thereafter act as a side-swipe feeler. In the present instance of the 20 invention, the feeler member 15 has pivotally mounted thereon at 24, a locking device comprising 25 a frontwardly-extending arm 25 having a shoulder 26 adapted to engage in front of a latch 27 carried by the feeler stand. A spring 28 normally acts to hold the front end portion of the arm 25 with the 30 shoulder 26 in locking engagement with the latch 27, the construction being such that when the parts are positioned as indicated in Figs. 1 and 2, the feeler member 15 will be 35 locked in a frontward position.

When the feeler is thus locked in frontward position, an important feature contemplates that it shall be confined to a measuring function, that is, that it shall enter the shuttle on each detecting beat and detect the 40 diameter of the filling; and a further feature of the invention in this respect contemplates that when the feeler member 15 has detected a predetermined diameter of filling, that it shall be released to perform its side-swipe 45 function.

In the present instance of the invention, these results are carried into effect by providing the feeler member 15 with the longitudinal slot 29 having an enlarged portion 30 50 in which slot the downturned end 31 of the latch 27 is adapted to operate, as best shown in Figs. 1 and 3. When the feeler member 15 is locked in frontward position, the downturned end of the latch 27 is engaged by the 55 narrow portion 29 of the slot, but when the feeler member returns to its full rearward and feeling position, the downturned end of the latch 27 operates in the enlarged portion 30 of the slot.

The locking device heretofore described as 60 pivoted at 24, has a part or projection 33 extending upwardly, and at one side thereof is adapted to be struck by either the front wall of the shuttle-box or the wall of the shuttle 65 itself, these being equivalent means, in order

to trip the locking device when the feeler member 15 enters sufficiently far into the shuttle owing to the decreased diameter of the filling therein.

From the construction described, it will be 70 apparent that when the feeler member 15 is locked in its front position as indicated in Figs. 1 and 2, it will be prevented from movement longitudinally of the shuttle and will act as a measuring feeler until as the 75 diameter of the filling in the shuttle becomes less and less, the part or projection 33 of the locking device will be struck by a rigid portion carried by the lay and trip the locking device from its holding relation with the 80 latch 27, thereby permitting the feeler member to move backward to its full feeling position. At this time the downturned end 31 of the latch 27 is in the enlarged portion 30 of the slot in the feeler member, thereby 85 freeing the feeler member to its side-swipe function.

The latch 27 is preferably pivoted to the base or support 10, as at 34, and is normally under the influence of a light spring 35, a 90 stop 36 on the under surface of the cover 11, Fig. 3, acting to prevent contraclockwise movement of the latch under the impulse of the spring 35 and serving to hold it in proper lock-latching position. This yielding action 95 of the latch 27 is desirable, because when the feeler member 15 is performing its side-swipe function, should the shuttle fail to be properly positioned in the box, the feeler member 15 may strike the wall of the shuttle, 100 causing the downturned end of the latch 27 to be engaged in front of the shoulder 36 of the feeler member, and the yielding action of the latch will permit the latch to move clockwise as the feeler member moves frontward and thereby prevent breakage.

When the feeler member 15 is released from its holding relation with the latch 27 and the feeler member is moved backward into the full feeling position, the downturned end of the latch 27 will ride along the frontwardly-extending edge 37 of the arm 25, as indicated in Fig. 3. At this time, if sufficient filling is present in the shuttle to continue the weaving operation, before 115 reaching the critical point, the roughened or serrated end portion 23 of the feeler member will engage the filling on a detecting beat and hold the end of the feeler member from movement longitudinally of the 120 shuttle; and when the filling has reached substantial exhaustion, and replenishment is desired, the roughened or serrated end portion 23 of the feeler member will no longer be held from movement longitudinally of the 125 shuttle as the lay beats up and filling replenishment will be effected through suitable connections with the feeler member, as will presently appear.

In the feeler motion of the type illustrated, 130

the feeler is subjected to the influence of means tending to move the feeler longitudinally of the shuttle on each detecting beat. This means may be variously contrived, and the invention is not restricted in this respect. In the present instance of the invention, the feeler carrier 16 has projecting from the side thereof, a lug 38 to which, is connected one end of a rod 39 provided with a collar 40, between which and a guiding stand 41 is interposed a spring 42, the action thereof normally tending to force the rod 39 endwise to the left, Fig. 1, and consequently move the feeler carrier and feeler member. The rod 39 has connected thereto at 43, one arm of a bell crank lever pivoted at 44 to the guide stand 41, the other arm 45 of said bell crank underlying an actuator 46 pivoted at 47 to an arm 48 rising from the transverse or 20 change shaft 49, substantially as more fully described in the prior application, Serial No. 78,586, filed February 16, 1916.

As set forth in said prior application, the actuator 46 has an end portion 50, adapted 25 to be engaged by a part 51 mounted on the weft hammer or cam follower, or an arm secured thereto. The lug or flange 52 and its coöperative relation with the part 51 on the weft hammer or cam follower may be substantially as fully described in said prior application.

During the operation of the loom, when a full working supply of filling is present in the shuttle, the feeler member will be locked 35 in a frontward position, and at such times will enter the shuttle on each detecting beat and detect the condition of the filling therein. At such times, the feeler member 15 is preferably prevented from side-swi^ee tendency. As hereinbefore described, the present instance of the invention shows the feeler member 15 mounted upon the feeler carrier 16 for movement toward and from the front of the loom, and to provide for the side 45 swi^ee movement of the feeler under the influence of its actuating means, such as the spring 42, the feeler carrier is mounted for movement longitudinally of the shuttle. This feature of the invention may be variously contrived, but in the present instance, the feeler carrier 16 is connected to the feeler stand or support 10 by a link 53, one end of which is pivoted to the carrier 16 at 54 and the other end of the feeler stand or support 50 55 at 55, suitable stops 56 being provided on the front portion of the feeler stand or support 10 to limit the side movement of the front end portion of the carrier, and stops 57 at the rear portion of the feeler stand to 60 limit the side movement of the rear portion of the carrier, the construction being such, that should the feeler member detect substantial exhaustion of filling on a detecting beat after it has been unlocked, the feeler 65 carrier and feeler member may be given a

movement longitudinally of the shuttle by the actuating means, such as the spring 42, to effect replenishment of filling. The lateral movement permitted the front end portion of the carrier 16 by the stops 56 is not sufficient to position the parts for replenishment of filling, but when the feeler detects substantial exhaustion of filling and its rear end is moved longitudinally of the shuttle, the increased movement thus afforded enables the parts to initiate replenishment of filling. The lateral movement of the carrier 16 may be effected first at its front end and then at its rear end on substantial exhaustion of filling, or such movements may be simultaneous, as will be readily apparent.

When the filling has become substantially exhausted and the feeler member has indicated or initiated a change of filling, it is desirable that the feeler member be returned 85 to its frontward or locked position and resume its measuring function. To this end, after the filling has been changed, and on the detecting beat following such change, the feeler member 15 engages the full filling 90 carrier and is moved sufficiently frontward thereby to cause the shoulder 26 of the arm 25 to engage in front of the latch 27, and thereafter the parts will remain in this position, and the feeler member will act as a 95 measuring feeler until it detects a predetermined condition of the filling in the shuttle, whereupon it will be freed to resume its full rearward feeling position as a side-swi^ee feeler.

The stop 57 may have an inclined portion 60 adapted to be engaged by a reversely inclined portion 61 on the feeler member to return the feeler member to the right, Fig. 2, after a side-swi^ee feeler action.

What is claimed is:—

1. In a feeler motion for looms, the combination of a feeler member, means normally acting to move the feeler member rearwardly into full feeling position, means 110 for locking the feeler member in a frontward position in opposition to said normally acting means, to enter the shuttle and engage the filling on each detecting beat, and a part carried by the locking means adapted 115 to be engaged by a part carried by the lay when the feeler member detects a predetermined diameter of filling to unlock the feeler member and permit it to move rearwardly to full feeling position prior to substantial exhaustion of the filling in response 120 to the normally acting means.

2. In a feeler motion for looms, the combination of a feeler member movable in a direction longitudinally of the shuttle when 125 the filling is substantially exhausted to effect replenishment of filling, a lock to hold the feeler member frontward from full feeling position and permit the feeler to enter the shuttle and engage the filling on each 130

detecting beat, and a part connected to the lock and adapted to be engaged by a rigid part on the lay prior to complete exhaustion of filling to trip the lock and permit the 5 feeler to move to feeling position, and means for effecting movement of the feeler longitudinally of the shuttle when substantial exhaustion of filling is reached.

3. In a feeler motion for looms, the combination of a side-swipe feeler member, yielding means normally acting to move the feeler member rearwardly to feeling position, means acting upon the feeler member to impart its side-swipe movement longitudinally of the shuttle, locking means for holding the feeler member forward from full feeling position and from side-swipe movement and permitting the feeler member to enter the shuttle and engage the filling 15 on each detecting beat, and a part carried by the locking means and engaged by the shuttle on a detecting beat when the feeler member indicates that the filling approaches substantial exhaustion to free the feeler member to both of said movements.

4. In a feeler motion for looms, the combination of a feeler member, a lock for holding the feeler member in a forward position until the filling approaches substantial 20 exhaustion and adapted to be struck by a part on the lay in front of the filling as the lay beats up to free the feeler member when the latter enters the shuttle a predetermined amount, and means for moving the feeler member longitudinally of the shuttle when the filling is substantially exhausted.

5. In a feeler motion for looms, the combination of a side-swipe feeler member, means for moving the feeler member rearwardly to feeling position, means for locking the feeler member forward of its feeling position to permit the feeler member to detect the diameter of the filling in the shuttle, means for locking the feeler member from side-swipe movement until the feeler member indicates the approach of substantial exhaustion and for then freeing the feeler member that it may move to full feeling position and on substantial exhaustion of the filling move longitudinally of the shuttle.

6. A feeler motion for looms, comprising, in combination, a feeler member movable toward and from the front of the loom to 55 measure the diameter of filling in the shuttle and movable longitudinally of the shuttle to effect filling replenishment, means for locking the feeler member from movement longitudinally of the shuttle and in a forward position until it detects a predetermined diameter of filling prior to substantial exhaustion and then freeing it to movement rearward and longitudinally of the shuttle.

65 7. A feeler motion for looms, comprising,

in combination, a feeler member having two detecting movements, one to measure or detect the diameter of the filling in the shuttle and the other in a different direction to effect a change in the loom operation when the filling is substantially exhausted, means for preventing movement of the feeler member to effect a change in the loom operation until the feeler member detects a predetermined condition of the filling prior to substantial exhaustion and thereupon to free the feeler member to such movement, and means connected to the feeler member to give the feeler member such movement when the filling reaches substantial exhaustion. 80

8. In a feeler motion for looms, the combination of a feeler member having two detecting movements, one for detecting the diameter of the filling in the shuttle and the other longitudinally of the shuttle to effect a change of filling, means for confining the feeler member to the first of these movements until it detects a predetermined diameter of filling and then freeing it to the second of these movements, means for moving the feeler member longitudinally of the shuttle to initiate a change of filling when it detects substantial exhaustion, and connections between the feeler member and said means. 90

9. In a feeler motion for looms, the combination of a feeler member adapted to be struck by the filling in the shuttle on each detecting beat, means for limiting the rearward movement of the feeler member until the filling in the shuttle approaches substantial exhaustion and then permitting further rearward movement of the feeler member, and means operative when the feeler member is permitted such further rearward movement to move the feeler member longitudinally of the shuttle should the filling be substantially exhausted. 100

10. In a feeler motion for looms, the combination of a feeler member to feel for the filling in the shuttle on each detecting beat and having a longitudinal and a side-swipe movement, a lock for limiting the longitudinal movement of the feeler member until the filling is used up to a predetermined degree prior to substantial exhaustion, means for tripping the lock when the feeler member detects that a predetermined diameter of filling in the shuttle has been reached, means for locking the feeler members from side-swipe movement longitudinally of the shuttle until the said lock is tripped, and means for giving the feeler member its side-swipe movement longitudinally of the shuttle when the filling reaches substantial exhaustion. 115

11. A feeler motion for looms, comprising in combination, a feeler member to feel for the filling in the shuttle on each detecting beat, a locking member coöperating with the feeler member for holding the feeler mem- 120 130

- ber in a frontward position and adapted to be struck by a part movable with the lay to trip the locking member prior to substantial exhaustion of filling that the feeler member may move to a rearward position, and means for moving the feeler member longitudinally of the shuttle when released by the locking member and the filling is substantially exhausted.
- 10 12. A feeler motion for looms, comprising, in combination, a feeler member to enter the shuttle on each detecting beat and feel for the filling, a locking device for limiting the distance that the feeler member may enter the shuttle during the presence of a working supply of filling, and adapted to be tripped to permit the feeler member to move farther into the shuttle when the filling approaches substantial exhaustion, and means for moving the feeler member in a direction longitudinally of the shuttle when the filling reaches substantial exhaustion.
- 15 13. A feeler motion for looms, comprising, in combination, a feeler member to enter the shuttle on each detecting beat and feel for the filling, a locking device for limiting the distance that the feeler member may enter the shuttle during the presence of a working supply of filling, connections between the feeler member and locking device to cause the latter to be set by frontward movement of the feeler member due to the presence of a full filling carrier after a replenishing operation, and a part connected to the locking device to be engaged by a part on the lay when the filling approaches substantial exhaustion to trip the lock, and means for moving the feeler member longitudinally of the shuttle when the filling reaches substantial exhaustion.
- 20 14. A feeler motion for looms, comprising, in combination, a feeler member, means normally acting to move it rearwardly, a lock mounted on the feeler member, a latch for engaging the lock to hold the feeler member in a frontward position, and a part carried by the lock for disengaging it from the latch by contact with the shuttle when the filling approaches but before it reaches substantial exhaustion to permit the feeler to move rearwardly to full feeling position.
- 25 15. A feeler motion for looms, comprising, in combination, a feeler member to feel for the filling in the shuttle, a lock pivotally mounted on the feeler member, a latch adapted to be engaged by the lock when the feeler mechanism is moved frontward by a full carrier in the shuttle on a detecting beat to hold the feeler member frontward, said lock having a part to be engaged by the shuttle wall to trip the lock and permit the feeler member to move rearwardly prior to substantial exhaustion of the filling.
- 30 16. A feeler motion for looms, comprising, in combination, a side-swi
- a support therefor, means for moving the feeler member longitudinally of the shuttle when the filling is substantially exhausted, and connections between the feeler member and support to permit the front end portion of the feeler member to move laterally due to the action of said moving means when the feeler end of the feeler member is engaged with a working supply of filling.
- 35 17. In a feeler motion for looms, the combination of a feeler member having two detecting movements, one toward and from the shuttle to measure or detect the diameter of the filling in the shuttle and the other longitudinally of the shuttle to effect a change in filling, a lock for locking the feeler member in frontward position and preventing movement of the feeler member longitudinally of the shuttle until the feeler member detects a predetermined diameter of filling and then freeing the feeler member that it may move rearwardly to full feeling position and be moved longitudinally of the shuttle when the filling becomes substantially exhausted, and means tending to move the feeler member longitudinally of the shuttle on each detecting beat.
- 40 18. In a feeler motion for looms, the combination of a feeler member, means tending to move the feeler member in a lateral direction on a detecting beat and prevented from effecting such movement by engagement of the feeler member with the filling until substantial exhaustion is reached, and means permitting the front end portion of the feeler member to move laterally under the action of said moving means when the rear end of the feeler member is held from lateral movement by the filling.
- 45 19. In a feeler motion for looms, the combination of a feeler member, means tending to move the feeler member in a lateral direction on a detecting beat and prevented from effecting such movement by engagement of the feeler member with the filling until substantial exhaustion is reached, a support for the feeler member, and a loose connection between the feeler member and support to permit the feeler member to move bodily laterally when the filling-engaging end of the feeler member fails to be held from lateral movement by the filling.
- 50 20. In a feeler motion for looms, the combination of a feeler member, a laterally movable carrier on which it is mounted, means tending to move the carrier and feeler member in a lateral direction on a detecting beat and to be prevented from effecting such movement by engagement of the feeler member with the filling until substantial exhaustion thereof, a support for the carrier, and connections between the carrier and support permitting the carrier to move bodily laterally when the feeler member fails to be held from lateral movement by the filling.

21. In a feeler mechanism for looms, the combination of a feeler member having two detecting movements, one for measuring or detecting the diameter of the filling in the shuttle and the other longitudinally of the shuttle to effect change of filling, a lock for holding the feeler member in a frontward position and confining the feeler member to the measuring movement until a predetermined diameter of filling is detected by the feeler, a member connected to the lock to be struck by a part carried by the lay to trip the lock and free the feeler to the second of its movements that it may initiate replenishment when the filling is substantially exhausted.

22. A feeler motion for looms, comprising, in combination, a feeler member movable

longitudinally of the shuttle and toward and from the front of the loom, means for locking the feeler member in a frontward position to enter the shuttle and measure the diameter of filling on each detecting beat, means acting when the feeler member is locked in frontward position to lock it from movement longitudinally of the shuttle, and freeing the feeler member to movement longitudinally of the shuttle when the locking means permits rearward movement of the feeler member to full feeling position, and means for tripping the locking means when the filling in the shuttle reaches a predetermined diameter.

In testimony whereof, I have signed my name to this specification.

EDWARD S. STIMPSON.
